DISPENSER WITH SLITTED RESILIENT
DIAPHRAGM

Arthur Hammerstein, Palatine, Ill.

Application September 14, 1945, Serial No. 616,316

1 Claim. (Cl. 222—490)

1

The invention relates to dispensing devices and more particularly to devices for dispensing comminuted materials as exemplified by sugar, salt, pepper, and the like from containers.

The invention has for its object to provide a novel device whereby the comminuted materials may be dispensed in an accurately-controlled manner and with maximum efficiency from a container.

The invention contemplates further the provision of a novel dispensing device which constitutes an efficient closure for the container with which it is combined and whereby the contents of said container normally are hermetically sealed against the effects of atmospheric changes and are adequately protected against contamination.

Another object of the invention is to provide a novel dispensing device which is germ-proof and which is readily cleaned and maintained in a sanitary condition.

In addition, the invention has for its object to provide a novel dispensing device which, in operation, develops an expelling force on the comminuted material whereby clogging, even during moist, atmospheric conditions, is prevented.

Other objects will appear from the description hereinafter, and the features of novelty will be pointed out in the claim.

In the accompanying drawing which illustrates an example of the invention without defining its limits,

Fig. 1 is a sectional elevation of the novel device in place upon a container;

Fig. 2 is an end view of the novel device;

Fig. 3 is a similar view showing the device as it appears during a dispensing period;

Fig. 4 is a cross-section on the line 4—4 of Fig. 1;

Fig. 5 is a cross-section of Fig. 1, and

Fig. 6 is a perspective view of the resilient control means forming part of the dispensing device.

As shown in the illustrated example, the novel dispensing device comprises an enclosing member consisting of a preferably cylindrical body 10 of any convenient dimensions and made of metal, glass, or plastics, or any other suitable materials. The outer open end of the body 10 is provided with an annular inwardly-directed flange 11 and with an internal shoulder 12 at a distance axially inwardly from the flange 11 as shown in Fig. 1. At its opposite end, the body 10 includes an annular axially-directed flange 13 which terminates at an inwardly-directed annular shoulder 14 as illustrated in Fig. 1. In close proximity to the annular flange 11, the body 10 is provided with openings 15 extending through the wall of said body

2

10 at diametrically opposite points for the accommodation of manually operable plungers 16 which normally project outwardly beyond said body through said openings and, at their inner ends, are provided with annular collars 17—the inner surfaces of which preferably are located in registry with the inner annular surface of the flange 11.

10 The control means, whereby the dispensing of the comminuted material is controlled, comprises a hollow resilient controlling member 18 having its outer end closed and provided with a slit 19 which, because of the inherent resiliency of the member 18, is maintained in a normally closed condition to thereby seal the container with which the dispensing device is combined. The resilient member 18, at its inner end, includes an annular hollow base section 20 fitted beneath the internal shoulder 12 and of a diameter to snugly fit the body 10 beneath said shoulder 12—said section having its inner end face preferably located flush with the shoulder 14. From the section 20, the resilient member 18 extends in the form of a hollow, cylindrical control section 21 preferably comprising an integral part of the inner end section 20 and dimensioned relatively to the body 10 to form an internal annular space 22 between said section 21 and the inner surface of the body 10 as illustrated in Figs. 1 and 5. The base section 20 primarily serves to fix the control section 21 in place and prevents its removal from the body 10, and has no other function.

In the assembled normal condition of the device, the collars 17 of the plungers 16 are located in surface engagement with the section 21 of the resilient member 18 with said plungers 16 projecting outwardly through the openings 15 and beyond the outer surface of the body 10 as shown in Figs. 1, 2, 3, and 4.

40 In practice, the novel dispensing device is combined with a cooperating container which, as shown, may consist of a body 23 provided at its open end with an axially projecting flange 24 dimensioned to form a horizontal external shoulder 25 at a distance from said open end of the container 23. The novel dispensing device is combined with this container preferably by forcing the axial flange 13 thereof over the axial flange 24 of the container 23 with the shoulder 14 in engagement with the end surface of the container flange 24 and the end face of the flange 13 in contact with the horizontal shoulder 25 of said body 23. In the preferred arrangement, the parts are so dimensioned that the flange 13 will fit over the flange 24 frictionally to a degree sufficient

to efficiently maintain the dispensing device in operative associate combination with the container 23. Obviously, other types of connecting means for combining the novel dispensing device in associated operative relation with the container may be substituted if desired. In any case, in the assembled condition, the control means or specifically the interior of the resilient member 18 is in open communication with the interior of the container 23.

In actual use, the comminuted material may be introduced into the container 23 either prior to the combination of the dispensing device therewith or by first removing said device from said container to enable this to be done.

When it is desired to utilize the novel device for dispensing the comminuted material from the container 23, the latter is held in an inverted position, and inward pressure is exerted upon the plungers 16, for instance, by the thumb and forefinger of the user to thereby resiliently deform the section 21 of the resilient member 18 inwardly. This inward deformation of the resilient member 18 by the inward action of the plungers 16 spreads the opposite surfaces of the slit 19 apart and opens said slit 19 to convert it into a discharge opening as shown in Fig. 3, through which a predetermined amount of the comminuted contents may be dispensed. That is to say by thus opening the slit 19 and inverting the container 23, the salt or other contents will at once start to flow, without requiring any other manipulation such as shaking the container. By manipulating the thumb and forefinger in a manner to regulate the pressure of the plungers 16 inwardly and to thereby control the extent of opening of said slit to a greater or lesser degree, the amount of flow may be efficiently regulated. In any case, the salt or other material is directed toward and confined to a given point of the object to be covered. This avoids sprinkling the salt or its equivalent indiscriminately, for instance, over a plate as is generally the case with conventional dispensing devices which require to be shaken.

After the desired quantity of salt or other comminuted material has been discharged from the container, pressure of the thumb and forefinger of the user is removed from the plungers 16 to permit the resilient member 18 to resume its normal expanded condition by the action of its inherent resiliency and coincidentally to force the plungers 16 outwardly to the normal positions shown in Fig. 1. This return of the resilient member 18 to its normal position also automatically restores the slit 19 to its closed position in which the container 23 is hermetically sealed, and the contents thereof are adequately protected against the effects of the atmosphere and from contamination from other sources.

It will be noted that the controlling means or, specifically, the resilient member 18, thereof is not subject to contact with the human fingers during the expulsion of the comminuted contents

of the container 23 and, accordingly, is protected against contamination from this source. The contents being expelled are consequently also free from human contact during the expulsion operation, and such contents are, therefore, also not likely to be contaminated.

The novel dispensing device is simple in construction and may be readily combined with the container for which it is designed and has the particular advantage that the essential controlling means is practically enclosed by and contained within the body 10 of the enclosing member. The resiliency and effectiveness of the controlling means is thereby maintained for a maximum period.

While the device is particularly effective for dispensing sugar, salt, pepper, and the like, it may be used with equal efficiency for dispensing other types of comminuted materials. Preferably, the resilient member 18, as a whole, is constructed of rubber or other suitable inherently resilient material—it being understood, however, that the use of other materials in its construction in combination with means for providing the desired resiliency is not precluded.

Various changes in the specific form shown and described may be made within the scope of the claim without departing from the spirit of the invention.

I claim:

A dispensing device adapted for communicating connection with a container including an enclosing member having an open end and a diametrically apertured side wall, an inwardly directed annular flange at the said open end, an outwardly directed interior shoulder on said member in axially spaced relation to said flange, a relatively stiff hollow resilient member positioned within the enclosing member in side wall spaced relation therewith, an enlarged external base on said member fitted beneath said shoulder and snugly engaging the enclosing member to hold the resilient member therein, an outer end wall of the resilient member having a normally closed slit in register with the open end of the enclosing member, separate opposed plungers slidably mounted through the apertures in the side wall of the enclosing member for deforming the resilient member to open the slit, and collars on the inner ends of said plungers positioned between the spaced side walls of said members.

ARTHUR HAMMERSTEIN.
